CLAIM

I claim the ornamental design for a faucet, as shown and described.

DESCRIPTION

FIG. 1 is a right side elevation of a faucet showing my new design, the other side being a mirror image thereof.

FIG. 2 is a front view thereof.

FIG. 3 is a rear view thereof.

FIG. 4 is a top view thereof.

FIG. 5 is a bottom view thereof; and,
FIG. 6 is a perspective view thereof.

1 Claim, 6 Drawing Sheets
